NEEDLE WEAVING LOOM

Raymond Dewas, Amiens, France

Application July 14, 1936, Serial No. 90,512
In France August 10, 1935

9 Claims. (Cl. 139—123)

The present invention relates to improvements in needle weaving looms fed from fixed weft bobbins and has for one of its objects to provide improved means for the guiding of the needles of these looms, whatever may be the type and whatever may be the method of driving the said needles, said means being adapted to be employed in combination with one another, thus forming an improved guiding device, or which may be employed separately.

These improvements consist in means of guiding the arms of the needles in their alternate passage in the shed and in means for the guiding of these arms, as well as the heels of the needles, in the channels.

These improvements are applicable particularly in those looms in which the needles for conveying and for pulling the weft thread in the shed are of the type described and claimed in the specifications accompanying my prior U. S. patent applications Ser. No. 725,885, filed May 16, 1934 (now Patent No. 2,072,161) and Ser. No. 19,576, filed May 3, 1935.

With regard to the improvements made in the guiding of the arms of the needles in the shed, they consist in the guiding of the arms in four principal opposed directions two by two, utilizing for this purpose means situated on the lower part of the arm of needles, facing the fell of the cloth (that is to say of the last weft thread inserted) and cooperating with other means situated on the forward part of the slay, also facing the fell of the cloth, which enables the shuttle race to be dispensed with, as well as with the use of the reed as a means of guiding, thus avoiding the inconveniences which in most cases arise from their employment.

With regard to the improvements provided in the guiding of the arms of the needles in their channels, these consist in employing certain of the means provided for the guiding of the arms in the shed, in combination with other similar additional guiding means which are situated on the upper part of the said arms, facing the reed, these various means cooperating with the inner walls of the channels arranged accordingly.

Finally, with regard to the improvements provided for the guiding of the heels of the needles in their channels, these consist in employing guiding means which are similar to those employed for the guiding of the arms in the channels but which have much larger surfaces, so that they may extend over at least two opposite sides of the heel, these means cooperating with the inner walls of the channels arranged accordingly.

The arrangement of these guiding means as a whole on the needles offers the advantage of preventing the coming into contact of the walls of the needles, properly speaking, with other surfaces liable to damage them.

The association of these improvements enables operation to be effected at great speed, lubrication being dispensed with and the warp threads being preserved as much as possible.

These improvements are described hereafter and shown diagrammatically in the attached drawings, merely as examples of the carrying out of the invention which are by no means limiting.

Fig. 1 is a plan view from above of one arm of the needle with its heel, arranged with a view to their guiding in accordance with the invention, the head of the needle not being shown, because this head, which is attached to the end of the arm, may be of any known type;

Fig. 2 is a side elevation seen from the fell of the cloth;

Fig. 3 is a cross section of the arm, taken on the line 3—3 of Fig. 2;

Fig. 4 is a cross section of the heel on the line 4—4 of Fig. 2;

Fig. 5 is a side elevation, seen from the fell of the cloth, showing the arm at the end of its forward stroke in the shed, at the moment when the thread is exchanged over; this figure also showing the channel in which the heel is located and which is fitted on one end of the slay, the sword and the reed being shown in part.

Fig. 6 is a cross section, on the line 6—6 of Fig. 5 showing the manner in which the guiding of the arm of the needles in the shed is carried out;

Figs. 7 and 8 are fragmentary views of details of one of the guides, shown in Fig. 6 attached to the fore part of the slay, facing the fell of the cloth;

Fig. 9 is a cross section taken on the line 9—9 of Fig. 5 showing the position of the arm of the needle and its guiding in the channel;

Fig. 10 is a cross section taken on the line 10—10 of Fig. 5 showing the position and the guiding of the heel in the channel;

Figs. 11 and 12 are cross sections of the heel, showing two variants in the construction of the latter;

Fig. 13 is a cross section of the heel and of its channel, showing a variant in the construction of these latter;

The needle, the arm and the heel of which are shown in Figs. 1, 2 and 5, which in a needle loom is at the left side of the loom, has in practice on

its end, the head (not shown) which passes the weft thread through the shed.

The needle situated at the right side of the loom and which also has at its end, a head which passes the weft thread through the shed, is formed similarly; therefore it has not been shown. Nevertheless, in accordance with the type of the head, the sections of the means for the guiding of the heel and of the arm may vary from those of the other needle.

According to these figures and with regard to the more important form of construction (Figs. 1 to 10), 1 is the arm of a tubular needle, preferably made of light metal, and having a square cross section. This metallic construction offers the advantage, as compared with wood, of avoiding all deformation under the influence of heat and dampness.

The end 1' of this arm, which enters into the shed, is arranged in any suitable way to receive the head or to form the head, partially or entirely. This head may be of any type whatever and particularly of the type described in my earlier applications already referred to.

25 The opposite end 1'' of this arm, which slides in the channel, carries the heel and also its stud 2 directing the alternate rectilinear movement of the needles, when this is attained, for example, by picking arm and connecting rod.

30 With regard to the guiding of the arm 1 in the shed, (Figs. 5 and 6) this is carried out, in accordance with the spirit of the invention, by a longitudinal strip 3 suitably profiled, attached to the lower part of the face 1^c of the arm 1 facing the fell of the cloth and extending preferably over the entire length of the said arm. This strip is assisted in its function by the guiding elements or guides 13 which are attached to the edge of the slay facing the fell of the cloth. These guides 13, which enter into the interior of the shed, across the lower sheet of the warp threads when the slay returns, are constructed in such a way as to ensure, without the assistance of other parts, than the strip 3, the guiding of the arm in the shed, in four principal directions which will be referred to hereafter, without the arm coming into contact either with the slay or with the reed.

50 Preferably this strip 3 has an angular cross section, mainly in order to reduce to a minimum the height of the guides 13 so that—and for other reasons—they may pass under the fabric easily when the weft is beaten up. The strip 3 is fitted in such a manner that its lower face 3^d projects slightly below the lower face 1^d of the arm 1, for the purpose of ensuring the guiding of the arm in the shed, as in the channel, in a vertical direction from below to above. The side face 3^e of its horizontal web is intended to ensure the guiding of the arm in the shed, as in the channel, in a horizontal direction from left to right. The upper face 3^b of this said horizontal web is intended for the guiding of the arm in the shed, in a vertical direction from above, to below and the side face 3^a is intended to guide the arm in the shed in a horizontal direction from right to left.

55 The guides 13 are arranged, at determined intervals and in suitable number, along the length of the slay 5, between the channels 8 and attached, by bolts or otherwise, on the edge of the slay facing the fell of the cloth, parallel to the teeth or dents 11 of the reed, the lower baulk 12 of which is held in the angle formed by the upper web and the horizontal web of the T-iron 5 forming the slay without a shuttle race.

60 75 These guides 13 are constituted of lugs, of metal

or other material, the upper ends of which are aligned on the passage, in the shed, of the strip 3 of the arms 1 of the needles, and at the greatest possible distance from the reed blades. This latter characteristic affords the very great advantage 5 of preserving to a considerable degree the warp threads which come in contact with the said guides, as well as the reed blades between which these threads are drawn in.

In order to ensure, on four sides and in accordance with the four principal directions, the guiding of the arms 1 in the shed by means of the guides 13 in combination with the strip 3, the upper ends of the guides 13 are cut out on the front part facing the arms 1 into the form of a hook, the inner profile of which corresponds partially to the profile of the strip 3 and consequently has faces 13^b, 13^c, 13^d and 13^a, so that the strip 3, when the needle advances into the shed, penetrates successively and slides in the hooks of the 20 said guides 13, being guided by the corresponding faces 3^b, 3^c, 3^d and 3^a on four sides, namely in vertical opposite directions from above to below and from below to above, and laterally in the directions opposite the side of the fell of the cloth and 25 of the side of the reed. The hooks might be arranged or combined with one another to compensate for eventual wear, as will be understood easily.

To facilitate the entry of the end of the strip 3 30 into the hook of the guides 13, the angles of the sloping parts of the latter preferably are rounded, as also is the entry end of the strip.

From the foregoing explanations it will be understood readily that as the result of this guiding of the arms 1 in the shed by means of the strip 3 and the guides 13, the heads of the needles move throughout their strokes and meet, in an absolutely accurate and certain manner, without strain of the assembly. For this reason, it is 40 possible to drive the needles at a high speed and with great frequency.

With a view to the guiding of the arm 1 in the channel 8, an additional strip 3' is mounted on and attached along the upper part of the face 1^c 45 of the arm 1, facing the reed 11; it is mounted in such a way that its upper face 3^b' projects slightly above the upper face 1^b of the arm 1, so as to effect guiding in the channel in a vertical direction from above to below, lateral guiding in a direction from right to left being ensured by the face 3^a' of this strip 3'. The guiding in the opposite lateral direction from left to right and guiding in a vertical direction from below to above are ensured by the faces 3^c and 3^d of the strip 3 for the guiding 55 in the shed, this strip 3 being diagonally opposite to the strip 3', so that by these very simple means the guiding is ensured rigorously.

The strips 3 and 3' do not extend over the whole height of the arm chiefly for to obtain 60 very great lightness and at the same time among other reasons, to allow, in the case of the application to needles working in accordance with the arrangements described in my earlier applications already referred to, of the sectionalizing 65 of the face 1^c of the tube of the pulling needle with a view to the passage of the blade ensuring the release of the weft thread.

With a view to the guiding of the heel of the needle in the channel 8, the end 1'' of the needle 70 is provided, in this form of construction, on two of its opposite faces 1^a and 1^c, with strips 4, covering the said faces and extending beyond them above and below the faces 1^b and 1^d, to the same extent as the faces 3^b' and 3^d of the 75

strips 3' and 3, the thickness of each of these strips 4 being the same as that of the strip 3 or 3' corresponding to it.

The strips 4, as a result of the conception of the assembly, are much reduced in length which contributes to the lightening of the needle and the reduction of the total space occupied by the loom.

The strips 3, 3' and 4 can be made of any other suitable material, for instance of vulcanized fibre.

With regard to the channel arranged at each end of the slay 5, it consists of a box 8 of cast-iron or other material, the side of which facing the fell of the cloth has a slot 9 throughout the whole of its length for the passage of the driving stud 2, said slot allowing of the needle 1 being withdrawn from the rear when this is required.

The mounting of the channel 8, at least when feeding is effected with a single weft thread, is carried out in such a way that the end which is directed towards the shed reaches (when a fabric is woven according the maximum width for which the loom is designed) the immediate neighborhood of the temples, in order to be able to reduce to the minimum the total length of the needle and consequently its weight and at the same time the whole space occupied by the loom. This involves, at the conclusion of the stroke beyond the shed, the re-entry of the head for a certain distance into the interior of the channel; and when the conveying needles are arranged to work according to the process described in my earlier applications already referred to, this involves, for the purpose of feeding the conveying needle, the arrangement in the side of the channel 8 which faces the reed, at its end which is directed towards the shed, of a slot 6 extending for a certain length and intended for the passage of the weft thread coming from the bobbin.

The attachment of the channel 8 on the T-iron 5 which forms the slay is ensured by means of screws passing through the middle horizontal web of the said T-iron 5 and entering the bosses 10 forming projections on the lower face of the channel 8.

The interior of the channel 8 is hollowed out in accordance with a rectangular section, for example, corresponding to the extreme outer dimensions of the arm and the heel with their strips.

By the combination of the inner faces of the channel 8^a, 8^b, 8^c and 8^d with the faces 4^a, 4^b and 4^d of the strip 4 of the heel on the side of the reed; and the faces 4^b, 4^c and 4^d of the strip 4 of the heel on the side of the fell of the cloth, the guiding of the heel in the channel is thus carried out in four principal directions.

By the combination of the same inner faces of the channel 8 with the faces 3^a and 3^b of the supplementary strip 3' and with the faces 3^c and 3^d of the strip 3, the guiding of the arm 1 in the channel 8 is carried out in the same way also on four sides.

As a result of the guiding in the four principal opposed directions which is ensured, as shown above, of the arm of the needle when it is in the shed and in the channel; as a result also of the shape and of the arrangement of the heel and of the dimensions of the surfaces in contact with the said channel, the whole in collaboration with great lightness of the needle, the guiding of the heel in the channel so that it may slide easily may be ensured, which, whilst increasing the speed, enables the lubrication of the channel to

be dispensed with and also the serious inconveniences resulting therefrom.

Further, as the result of this same guiding of the heel and of the arm through the whole length of the channel, it will be appreciated that the needle, when in the channel, can stand up, without strain, to the various reactions due, among others, to the beating up of the weft.

The strips 4 on the heel may cover all the faces of the end 1" of the arm 1 entirely or partially.

Fig. 11 shows a method of covering the faces 1^a and 1^c of the heel totally and the faces 1^b and 1^d of the heel partially.

Fig. 12 shows a method of covering the faces 1^a, 1^b, 1^c and 1^d of the heel totally by a sheath 4.

Fig. 13 shows a method of covering the faces 1^a, 1^b, 1^c and 1^d of the end 1" of the needle 1 forming the heel totally by means of the four strips 4, the inner profile of the channel 8 conforming closely to the outer profile of the strips. When a tube with sharp angles is employed, the projecting angles of this channel are removed and rounded off, as shown at 8^e, so as not to come into contact with the said angles of the tube. The four strips 4 afford the advantage of a very large contact surface with the channel, as a result of which wear is still further reduced. As the parts of the channel 8 which come into contact with the strips of the arm have not been altered, the working of the whole remains the same.

In certain cases the reed may share in the guiding of the arm in the shed. For this purpose the profile of the hooks of the guides 13 is altered in such a way as to guide the strip on the faces 3^b, 3^c and 3^d only, that is to say in vertical directions from above to below, lateral from left to right and vertical from below to above, whilst lateral guiding from right to left is ensured by the sliding of the face 3^a of the strip 3' against the reed, the latter, for this purpose, being situated in the prolongation of the inner vertical face 8^a of the channel.

In other cases a shuttle race may be employed for guiding the arm in the shed, from below to above, making use of the reed for guiding from right to left, or again the part of the hooks acting upon the face 3^a of the strip 3 may be employed. The shuttle race is then notched at the location of the guides 13 to allow of their being mounted.

It is to be understood that, without departing from the spirit of the invention, alterations, improvements or additions may be introduced and the employment of equivalent means may also be considered.

For example, the section of the strips is not invariable and these may have other shapes or another number of faces, the hooks of the guides as well as the channels having corresponding profiles so as to ensure guiding on another number of faces or in another number of directions. In the same way the strips of the heel and of the arm need not go beyond the levels of the tube, for example if the channel 8 is given the section shown in Fig. 13.

Similarly the strips on the arm and on the heel may be made in a single piece, of fibre or of moulded material, for example. Also when they are made of moulded material, for example with a basis of synthetic resin, the arm itself and its strips and also the head, may be made in a single piece and the arm may share in the sliding of the faces of the channel, thus increasing the already considerable contact surface. The sur-

faces which come into contact with the guides may also be covered with vulcanized fibre or with other resistant material.

5 Further the slot 9 and the stud 2 may be on another face of the channel, for example, if the drive of the needle were carried out by setting the stud 2 directly into motion, by means of a long stroke grooved cam arranged near the channel.

10 Finally these improvements will also be applicable to looms in which there are several pairs of needles bound by their heels.

I claim:

15 1. A weft inserting mechanism for looms, comprising the combination with a slay and a shed-forming mechanism, of a needle element including a shed penetrating portion and a heel portion, a guide channel connected to said slay at one side thereof and positioned adjacent the side 20 of the shed where said shed penetrating portion enters, means carried by said heel portion for engaging said guide channel to guide said heel portion to prevent lateral and vertical movement, a longitudinal rib carried by said shed penetrating portion and facing the fell of the cloth and a plurality of spaced guide members mounted at intervals on said slay engaging said rib during the penetrating movement, said rib and said guide members being so constructed that said shed penetrating portion will be guided to prevent lateral and vertical movement, and means for moving the needle through the shed.

25 2. A weft inserting mechanism for looms, comprising the combination with a slay and a shed-forming mechanism, of a needle element including a shed penetrating portion and a heel portion, a guide channel connected to said slay at one side thereof and positioned adjacent the side of the shed where said shed penetrating portion enters, means carried by said heel portion for engaging said guide channel to guide said heel portion to prevent lateral and vertical movement, a longitudinal L-shaped rib carried by said penetrating portion, a plurality of spaced guide members mounted on said slay at intervals, said guide members including means engaging said L-shaped rib during the penetrating movement to guide said shed penetrating portion to prevent lateral and vertical movement and permit penetration thereof into the shed and means for moving the needle through the shed.

35 3. A weft inserting mechanism for looms, comprising the combination with a slay and a shed-forming mechanism, of a needle element including a shed penetrating portion and a heel portion, a guide channel connected to said slay at one side thereof and positioned adjacent the side of the shed where said shed penetrating portion enters, means carried by said heel portion for engaging said guide channel to guide said heel portion to prevent lateral and vertical movement, a longitudinal L-shaped rib carried by said penetrating portion, a plurality of spaced guide members mounted on said slay at intervals, said guide members including a pair of fingers engaging said rib during the penetrating movement to guide said shed penetrating portion to prevent lateral and vertical movement and permit penetration into the shed, and means for moving the needle through the shed.

40 4. A weft inserting mechanism for looms, comprising the combination with a slay and a shed-forming mechanism, of a needle element having a substantially rectangular cross section and including a shed penetrating portion and a heel

portion, a guide channel connected to said slay at one end thereof and positioned adjacent the side of the shed where said shed penetrating portion enters, means carried by said heel portion for engaging said guide channel to guide said heel portion to prevent lateral and vertical movement, an L-shaped longitudinal rib carried by said shed penetrating portion and extending along the side facing the fell of the cloth to be woven and protruding slightly below the lower surface of said penetrating portion, a plurality of spaced guide members mounted on said slay at intervals, said guide members including means engaging said L-shaped rib during the penetrating movement to guide said shed penetrating portion to prevent lateral and vertical movement and permit penetration thereof into the shed, means for moving the needle through the shed.

45 5. A weft inserting mechanism for looms, comprising the combination with a slay and a shed-forming mechanism, of a needle element having a substantially rectangular cross section and including a shed penetrating portion and a heel portion, a guide channel connected to said slay at one end thereof and positioned adjacent the side of the shed where said shed penetrating portion enters, means carried by said heel portion for engaging said guide channel to guide said heel portion to prevent lateral and vertical movement, an L-shaped longitudinal rib carried by said shed penetrating portion and extending along the side facing the fell of the cloth to be woven and protruding slightly below the lower surface of said penetrating portion, a plurality of spaced guide members mounted on said slay at intervals, said guide members including means engaging said L-shaped rib during the penetrating movement to guide said shed penetrating portion to prevent lateral and vertical movement and permit penetration thereof into the shed, a second longitudinal rib carried by said shed penetrating portion and mounted substantially diagonally opposite to said first mentioned rib and protruding slightly above the upper surface of said shed penetrating portion, said ribs being constructed to engage said guide channel when the shed penetrating portion is inserted into and withdrawn from the shed whereby said shed penetrating portion will be continually and evenly guided to prevent lateral and vertical movement while it is in the guide channel, and means for moving the needle through the shed.

60 6. A weft inserting mechanism for looms, comprising the combination with a slay and a shed-forming mechanism, of a needle element having a substantially rectangular cross section and including a shed penetrating portion and a heel portion, a guide channel connected to said slay at one end thereof and positioned adjacent the side of the shed where said shed penetrating portion enters, means carried by said heel portion for engaging said guide channel to guide said heel portion to prevent lateral and vertical movement, an L-shaped longitudinal rib carried by said shed penetrating portion and extending along the side facing the fell of the cloth to be woven and protruding slightly below the lower surface of said penetrating portion, a plurality of spaced guide members mounted on said slay at intervals, said guide members including means engaging said L-shaped rib during the penetrating movement to guide said shed penetrating portion to prevent lateral and vertical move- 65

ment and permit penetration thereof into the shed, a second longitudinal rib carried by said shed penetrating portion and mounted substantially diagonally opposite to said first mentioned rib and protruding slightly above the upper surface of said shed penetrating portion, said ribs being constructed to engage said guide channel when the shed penetrating portion is inserted into and withdrawn from the shed whereby said 10 shed penetrating portion will be continually and evenly guided to prevent lateral and vertical movement while it is in the guide channel, means for moving the needle through the shed and slots in said guide channel one of said slots accommodating said last mentioned means, the other one of said slots permitting the passage of the weft thread arriving from the bobbin and passing to the selvedge.

7. A weft inserting mechanism for looms, comprising the combination with a slay and a shed-forming mechanism, of a needle element having a substantially rectangular cross section and including a shed penetrating portion and a heel portion, a guide channel connected to said slay at one end thereof and positioned adjacent the side of the shed where said shed penetrating portion enters, means carried by said heel portion for engaging said guide channel to guide said heel portion to prevent lateral and vertical movement, said means including guide strips mounted on opposite sides of said heel portion

and protruding slightly above and below the upper and lower surfaces of said heel portion, a longitudinal L-shaped rib carried by said shed penetrating portion and extending along the side facing the fell of the cloth to be woven and protruding slightly below the lower surface, a plurality of spaced guide members mounted at intervals on said slay, said guide members including means engaging said L-shaped rib during the penetrating movement to prevent lateral 10 and vertical movement, a second longitudinal rib carried by said shed penetrating portion and mounted substantially diagonally opposite to said first mentioned rib and protruding slightly above the upper surface of said shed penetrating portion, said ribs being constructed to engage said guide channel when the shed penetrating portion is inserted into and withdrawn from the shed, whereby said shed penetrating portion will be continually and evenly guided to prevent lateral and vertical movement while it is in the guide channel and means for moving the needle element through the shed.

8. A weft inserting mechanism according to claim 7 in which said guide strips entirely surround said heel portion.

9. A weft inserting mechanism according to claim 7 in which said guide strips only partly surround said heel portion.

30 RAYMOND DEWAS.
